SWIVEL ELECTRICAL CONNECTER

Frederick W. Fries, Rochedale, N. Y.

Application May 26, 1934, Serial No. 727,625

1 Claim. (Cl. 173—324)

This invention relates to a swivel electrical connector, and more particularly to that type which is intended to be mounted in the service cords or drop-lights, flat-irons, soldering-irons, 5 and other electrical appliances where the service cord is liable to become twisted and entangled.

The object of the invention is to provide an electrical connector to be mounted in a service or drop cord, whereby the cord may be twisted without 10 entangling the same.

Another object of the invention is to provide a connector of this kind whereby a perfect swivel connection is provided for the wires forming the circuit without in any way interrupting or impairing the efficiency of the service.

Another object of the invention is to provide a swivel connector that shall be simple of construction, contain few parts, and be easily installed in the line.

Another object of the invention is to provide a swivel connector in which the wires are so held as to produce no strain thereon, and which will prevent the wires from becoming loose or breaking off.

With these and other objects in view, my invention consists in certain new and useful construction and combinations of parts as will hereinafter be fully described and claimed, and further illustrated in the accompanying drawing, 30 which form a part hereof, and in which like figures of reference refer to corresponding parts in all of the views, and it is understood that slight changes may be made without departing from the spirit of the invention.

35 In the drawing:

Figure 1 shows a side elevation of the device as attached in a service cable.

Figure 2 is a longitudinal sectional view, taken on the center line.

40 Figure 3 is a plan view partly in section and with the two upper casings removed therefrom.

Figure 4 is a cross sectional view, taken on the line 4—4 of Figure 1.

Figure 5 is a cross sectional view, taken on the 45 line 5—5 of Figure 1.

Figure 6 is a cross sectional view, taken on the line 6—6 of Figure 1.

Referring to the drawing:

The device comprises a four part shell or casing, 10, 11, 12 and 13 all of insulating material, the two parts 10 and 11 being the same, and the two parts 12 and 13 being like each other; the parts 10 and 11 being clamped together by the screws 14, and the parts 12 and 13 being clamped together by the screws 15, which have their heads

and nuts in the depressions formed in said casings.

Each of said casings is formed with depressions which when the parts are clamped together will register with each other and provide a mounting for the several parts of the connector and 5 the electrical wires.

The swivel mechanism comprises a washer 16 of insulating material which is placed between the abutting ends of the parts 10—11 and 12—13, and said washer is formed with a central bore 10 within which the pivot bolt 17 is rotatably mounted; said bolt 17 having secured thereon a circular block of insulating material 18 and the collector ring 19, and retained under the nuts 9 upon said bolt 17 and in contact with the insulating washer 15 33 which is similar to the washer 16, is a terminal arm 20, the outer end of which is provided with the terminal binding screw 21, having the usual washer and nut; while secured under the head of the pivot bolt 17 and in contact with the washer 16 and head of the bolt 17 is a similar terminal arm 22, having the binding screw 31.

Upon and outside of the collector ring 19 is rotatably mounted the collector ring 23, and this collector ring 23 is provided with a terminal arm 25 30 integral therewith and extending through a slot formed in the washer 16, and is provided with the binding screw 24.

The inner collector ring 19 is also formed with an integral terminal arm 25 which extends 35 through a slot formed in the insulating washer 33 and which is also provided with the binding screw 26.

Adjacent the ends of the connector casings 10, 11, 12 and 13 are formed the semi-circular grooves 27 communicating with the cable openings 28, and within which the wires 29 are clamped by the joining together of the casing parts, and in such a manner that no strain is placed upon that part of the bare wire that is retained under the 40 binding screws.

It may here be stated that for clearness in the drawing, the grooves 27 and some other portions of the depressions in the casings have been shown as slightly larger than the parts of the apparatus 45 that are to be mounted therein, but in practice the grooves 27 will form a tight fit for the wires, so as to have a clamping action thereon.

It will thus be seen that while the washer 16 is retained by the pivot bolt 17 in a rotary relation with those parts of the device which are mounted in the casings 10 and 11, and that the bolt 17 does not rotate upon the block 18, that the collector ring 23 rotates upon the block 18 and bolt 17, but does not rotate with relation 55

to the parts mounted within the casings 12 and 13, and the washer 33 is retained in a non-rotatable relation with these parts, but rotates upon the bolt 17.

5 Having thus described my invention, what I claim as new and desire to secure by Letters Patents, is:

10 In a swivel coupler for electrical conductors, composed of two members of insulating material each having one squared end and one rounded end and each of said members comprising two parts detachably secured together, semi-circular wire receiving channels formed in each member adjacent their rounded ends, terminal receiving recesses formed in each member and communicating with the wire receiving channels and wire terminals located therein, one of said members provided with a circular recess communicating with the terminal recesses therein, an insulating washer located between the squared ends of said members and provided with an axial bearing and

15 a slot, a second insulating washer mounted within the circular recess and formed with an axial bearing and a slot, an insulating block located between said washers for spacing the same apart, a pivot bolt extending through the bearings in 5 said washers and block, a pair of concentric collector rings mounted in the circular recess around the insulating block in rotatable contact with each other, an arm secured to and extending from the inner ring through the slot in the second 10 washer and secured to one of the wire terminals in said member, an arm secured to and extending from the outer ring through the slot in the first washer and secured to one of the wire terminals in the other member, and a terminal arm 15 located in each of said members and having one end rotatably secured to the pivot bolt and the other end to the remaining wire terminal in each of said members.

FREDERICK W. FRIES. 20
